UNITED STATES PATENT OFFICE

AUGUSTUS WILKES GUDGE, OF NEWARK, NEW JERSEY, AND EARL WENSLEY, OF CICERO, ILLINOIS, ASSIGNORS TO WESTERN ELECTRIC COMPANY, INCORPORATED, OF NEW YORK, N. Y., A CORPORATION OF NEW YORK

METHOD OF PRODUCING ARTICLES FROM SHEET MATERIAL

Application filed June 9, 1928. Serial No. 284,208.

The invention relates to a method of producing articles from sheet material, and more particularly to a method of forming damping rings for acoustic apparatus.

Objects of the invention are to provide a method of quickly and economically producing articles of sheet material.

In accordance with the general features of the invention, a method is provided in which

10 a ribbon of paper of suitable width is first preliminarily formed in a longitudinal direction and then further formed in order to obtain a predetermined width in the longitudinal folds produced therein. After the 15 ribbon is folded it is moved between a pair of guide rollers from which it passes between a plurality of spring pressed blades to a pair of pressure rolls which crease the folded paper to form a tape of predetermined width, 20 and the damping rings are then stamped from the tape by a die having a larger diameter than the tape leaving an integral connection between the leaves of the damping ring.

It is believed that a complete understanding of the invention may be had by reference to the following description, taken in conjunction with the accompanying drawing, in which

30 Fig. 1 is a side elevation of the apparatus for forming damping rings by which the method may be practiced;

Fig. 2 is an enlarged view of a portion of the forming apparatus;

Fig. 3 is a fragmentary plan view of the 35 apparatus taken on line 3—3 of Fig. 1;

Fig. 4 is a cross sectional view of a portion of the apparatus taken on line 4—4 of Fig. 1;

Fig. 5 is a detailed view taken on lines 5—5 of Fig. 1;

40 Fig. 6 is an elevation of a portion of the feeding mechanism with a section through a portion of the forming mechanism;

Fig. 7 is an end view of a portion of the forming mechanism with a cross section through a portion of the advancing mechanism;

45 Fig. 8 is an elevation of a portion of the advancing mechanism taken on line 8—8 of Fig. 7;

50 Fig. 9 is a detailed view of an article made

in accordance with the invention, showing the leaves of the damping ring extended, and

Figs. 10 and 11 show a plan and end view, respectively, of the article as it appears when completed by the apparatus with its composite parts in normal position.

Referring to the drawings, an apparatus for practicing the method is shown mounted upon a base 15. At one end of the base a roll of paper 16 is mounted upon an upright spindle 17 upon which it is resiliently held by a pair of springs 18 attached to the middle of the spindle. The spindle 17 is mounted in a cradle 20 pivoted at 19 permitting the edge of the roll to align itself with a vertical guide 21. The paper passes from the roll in the form of a ribbon around the guide 21 to a preliminary forming member 22 which is provided with an undulated slot (Fig. 5) whose undulations correspond to the number of folds to be imparted to the paper. From the preliminary forming device 22 the partially folded ribbon which has received its preliminary outline passes between a plurality of dove-tailed blades 23 (Fig. 4) which are alternately supported on opposite sides of the ribbon. Each of the blades 23 is mounted in a tapering bar and the bars are supported upon standards 24 and 25 in such a manner that the blades converge in the direction of travel of the ribbon so that the ribbon enters the blades as it is formed by the preliminary forming device and leaves the blades in the form of a composite tape of six leaves. The bars supporting the outside

blades are carried by bolts which are movable in slots upon loosening of the thumb screws 26 to permit a separating of the blades for the purpose of threading the ribbon of

paper through the blades when a new roll of paper is inserted in the apparatus. It is quite important that the leaves of the folded paper should have a predetermined width so as to leave a connection of uniform length

between the leaves when a damping ring is later stamped therefrom. The width of the leaves is determined by the amount of overlapping or dove-tailing of the blades 23. In order to adjust the amount of overlapping of the blades, the standard 24 is mounted

upon a slideable member 31, a portion of which engages a T-shaped slot in the base. A clamping member 32 occupies the T-portion of the slot and serves to clamp the member 31 in place upon the operation of a cam 33 which exerts an upward force upon a bolt 34 to which the clamping member 32 is attached.

The folded ribbon passes from the blades 23 through a pair of guide rolls 35 to a plurality of parallel blades 36 which are alternately supported on opposite sides of the ribbon. On the one side, the blades are carried by a support 37 and on the other side by an arm 38 which pivots about the point 39. The arm 38 also carries a pair of compression members 41 (Fig. 7) which engage the blades 36 at the point where they contact with the folded ribbon and exert a pressure thereon. A spring 42 (Fig. 3) engages the arm 38 and serves to hold it in operative position. In order to thread the paper tape through the blades 36 the arm 38 may be swung about its pivot 39 to render the blades more accessible. The folded paper passes from the blades 36 between creasing rolls 43 and 44 and thence to a punch press 45 in which the damping rings 46 are stamped from the tape.

The roll 43 is mounted upon a shaft 49 and mounted upon the same shaft is a toothed wheel 40 (Fig. 8) which is engaged by a plurality of pawls 47. The pawls 47 are mounted in a cup-shaped opening of a wheel 48 which is loosely mounted upon the shaft 49. A link 51 connects the wheel 48 to a bell crank lever 52 which is actuated by an adjustable link 53 attached to the plunger of the punch press. The bell crank lever is provided with a slot 54 in which a slideable member 55 is adjustably mounted for the purpose of varying the amount of movement of the link 51 and the travel of the tape. When the plunger of the punch press descends, the pawls 47 will slide over the toothed wheel 40, and when the plunger ascends, the pawls will engage the teeth on the wheel 40 to rotate the roll 43 an amount sufficient to advance an unstamped portion of the tape under the plunger of the press. A handle 50 is also provided by which the rolls may be rotated manually in threading a ribbon into the apparatus.

The rolls 43 and 44 are interconnected by gears 56 and 57, causing the rolls to have the same peripheral speed. The lower roll is mounted upon an arm 58 which is pivoted at 59, permitting the roll to be dropped for the purpose of threading the paper tape through the rolls. The lower roll is maintained in pressing engagement with the upper roll and the paper tape by means of a spring pressed plunger 61 and may be disengaged therefrom by moving a cam shaped lever 62 to its vertical position.

In the operation of the apparatus, the

paper ribbon passes over the guide 21 to the preliminary forming apparatus 22 where the ribbon is longitudinally formed into a plurality of undulations. The paper ribbon is then passed to the overlapping converging blades where folds of a predetermined width are imparted to the paper and from which the paper emerges in the form of an accordion pleated tape of a predetermined width passing through guide rollers 35 and between blades 36 into the rolls 43 and 44 where the edges of the tape are firmly pressed together to form a crease. The paper is then intermittently advanced to a punch press by the mechanism described above. The diameter of the punch is made slightly larger than the width of the folded leaves so that when a damping device 46 is stamped from the paper tape a narrow hinge 61 will remain on opposite sides of the damping device connecting the various leaves as shown in Fig. 9. It will be seen therefore that it is very important that the paper tape be folded in such a manner that the leaves are always of a uniform width in order that the hinge or connection between the leaves shall have a uniform length. Figs. 9, 10 and 11 show a damping device in which the leaves are interconnected by hinges or connections 61 which form cords of the annular periphery of the damping device.

It will be understood that the embodiment of the invention herein described and illustrated is merely a convenient and useful form of the invention which is capable of many other modifications without departing from the spirit and scope of the invention.

What is claimed is:—

1. A method of forming an article, which consists of producing a plurality of longitudinal folds of uniform width in a ribbon of material, creasing the material along the folded edges, and stamping therefrom an annular member having a greater diameter than the width of the folded material.

2. A method of forming an article, which consists of folding a sheet of material into a plurality of leaves of a predetermined width and stamping therefrom an annular member having a greater diameter than the width of the leaves, thereby leaving a connection between the leaves.

3. A method of forming an article, which consists of producing a plurality of longitudinal undulations in a ribbon of material, converging the undulations until a folded tape is obtained, and stamping an annular member therefrom having a greater diameter than the width of the folded tape.

4. A method of producing a damping device, which consists of folding material into a plurality of leaves having a predetermined width, and stamping a damping device therefrom leaving a portion of the folded edges as a hinge for connecting the leaves.

5. A method of producing an article which consists in forming from sheet material an accordion pleated tape having leaves of a predetermined width, and then stamping an annular member therefrom having a greater diameter than the width of the leaves.
6. A method of producing an article which consists of forming from sheet material an accordion pleated tape having leaves of a predetermined width, creasing the edges of the leaves, and then stamping an annular member therefrom having a greater outside diameter than the width of the leaves, thereby leaving portions interconnecting the leaves.
